WILLIAM S. STAPLEY, OF BRIDGEPORT, CONNECTICUT, ASSIGNOR TO THE BRIDGEPORT BRASS COMPANY, OF BRIDGEPORT, CONNECTICUT, A CORPORATION OF CONNECTICUT.

CANISTER-TOP.

No. 827,821.

Specification of Letters Patent.

Patented Aug. 7, 1906.

Application filed January 11, 1906. Serial No. 295,592.

To all whom it may concern:

Be it known that I, WILLIAM S. STAPLEY, a citizen of the United States, residing at Bridgeport, county of Fairfield, State of Connecticut, have invented a new and useful Canister-Top, (Case A,) of which the following is a specification.

This invention relates to the class of canister-tops in which a neck or nozzle and a cap 10 adapted to rotate thereon are provided with openings which when placed in alinement permit the contents of the canister to be poured out and when placed out of alinement close the canister; and the invention has for 15 its object to provide a canister-top of this character which shall be simple and inexpensive to produce, strong and durable, and in which the cap when placed in the closed position or in either the open or closed position, 20 if preferred, will remain there until power is applied to move it to the other position, so that filled canisters may be shipped and handled freely without danger of leakage. In order to accomplish this result at a minimum 25 cost of production and at the same time produce a canister-top that shall be neat and attractive in appearance and while easy to operate will be self-locking in the closed position or in both the open and closed positions, 30 I have devised the novel structure of which the following description, in connection with the accompanying drawings, is a specification, reference characters being used to indicate the several parts.

35 Figure 1 is an elevation of my novel canister-top, the cap being in the closing position; Fig. 2, a vertical section on the line 2 2 in Fig. 1; Fig. 3, a transverse section on the line 3 3 in Fig. 2 looking down; Fig. 4, a vertical 40 section on the line 4 4 in Fig. 5 looking in the direction of the arrow, illustrating a variant form of the invention differing only in that the cap is made shorter and the pouring openings are in the end of the neck and cap 45 instead of in the side, as in the other form; and Fig. 5 is a plan view, partly broken away, corresponding with Fig. 4.

50 10 denotes the top, and 11 the neck or nozzle, which may be formed integral therewith from a blank of sheet metal and is provided 55 in either the top or side, as preferred, with a pouring-opening 12.

13 denotes the cap, which is likewise formed

from sheet metal and is provided with a corresponding pouring-opening 14, which when placed in alinement with the opening in the neck permits the contents of a canister to be poured out and when moved wholly out of alinement with the opening in the neck closes the canister.

15 denotes a groove or depression in the edge of the end of the neck—that is, at the angle formed by the intersection of the sides of the neck with the end thereof, this point affording the greatest strength to insure durability. At one or both ends of this groove I provide a locking depression 16. The cap is provided with an inwardly-extending lug 17, formed by depressing the metal thereof, which is adapted to engage groove 15 and 60 also to engage locking depressions 16 to lock the cap at either extreme of its movement—that is, with the pouring-opening in the cap either in alinement or wholly out of alinement with the pouring-opening in the neck. 65 At or near the end of the cap I preferably form a circular rib 18, which, however, is not an essential feature of the invention, but is merely provided for ornament. In the form illustrated in Figs. 4 and 5 this rib is formed 70 at the edge of the cap—that is, at the intersection of the sides and top—and is knurled for convenience in rotating the cap. In the form illustrated in Figs. 1 and 2 this rib is not knurled; but the cap is extended above the 75 end of the neck for purposes of ornament only and is provided at its outer end with a knurled rib 19 for convenience in rotating the cap. Near the lower end of the cap in both forms I provide a circular rib 20. In 80 assembling the cap is placed over the neck, after which the metal of the neck is spun outward to form a rib 21, which engages rib 20 and locks the cap in place upon the neck, the engagement of rib 21 with the inner face of 85 rib 20 being loose enough to permit the cap to be turned easily. The engagement of lug 17 on the cap with groove 15 in the edge of the neck is also free enough to permit the cap to be turned easily, but not to move in either 90 direction of its own weight. The locking of the cap in the closed position or in both the open and closed positions, if preferred, is effected by the engagement of lug 17 with the locking depressions at the ends of groove 15. 95 It is of course important that the cap be self- 100

locking at the closed position, so that filled canisters provided with my novel top may be shipped and handled freely without danger of the contents leaking out. For that reason I always provide a locking depression at the end of the groove, which is engaged by the lug when the cap is in the closing position—that is, when the pouring-openings in the cap and neck are out of alinement. As it is frequently considered desirable that the cap be self-locking in the open as well as the closed position I have illustrated a locking depression at each end of the groove which is adapted to be engaged by the lug on the cap to lock the cap at either extreme of its movement.

Having thus described my invention, I claim—

1. A canister-top comprising a neck and a cap having corresponding pouring-openings, said neck being provided with a groove at the angle formed by the top and side of said neck and at the end of said groove with a locking depression, the cap being provided with an inwardly-extending lug engaging said groove

and depression, and said cap and neck being provided near their lower ends with corresponding circular ribs whereby the cap is retained upon the neck but is permitted to rotate and is self-locking in the closed position through the engagement of the lug with the locking depression. 30

2. A canister-top comprising a neck and a cap having corresponding pouring-openings, said neck being provided with a groove at the angle formed by the top and side of said neck and at each end of said groove with a locking depression, the cap being provided with an inwardly-extending lug engaging said groove and adapted to engage said depressions 40 whereby the cap is made self-locking at both extremes of its movement, and means for retaining the cap upon the neck while permitting rotation of the cap.

In testimony whereof I affix my signature 45 in presence of two witnesses.

WILLIAM S. STAPLEY.
